UNITED STATES PATENT OFFICE.

EDWIN W. WEBB AND NICHOLAS C. THALHEIMER, OF CHICAGO, ILLINOIS, ASSIGNEES
TO STANDARD CAR TRUCK COMPANY, OF CHICAGO, ILLINOIS, A CORPORATION OF
NEW JERSEY.

SIDE BEARING FOR CARS.

1,284,840.

Specification of Letters Patent. Patented Nov. 12, 1918.

Application filed August 21, 1918. Serial No. 212,142.

To all whom it may concern:

Be it known that we, EDWIN W. WEBB and NICHOLAS C. THALHEIMER, citizens of the United States, residing at Chicago, in the county of Cook and State of Illinois, have invented certain new and useful Improvements in Side Bearings for Cars; and we do hereby declare the following to be a full, clear, and exact description of the invention, 10 such as will enable others skilled in the art to which it appertains to make and use the same.

Our invention relates to improvements in side bearings for cars and the like, of the 15 type disclosed and broadly claimed in a pending application executed of even date herewith and filed by Franklin L. Barber and Edwin W. Webb and also an application executed by Edwin W. Webb of even date 20 herewith.

To the above end, generally stated, the invention consists of the novel devices and combinations of devices hereinafter described and defined in the claims.

25 In the accompanying drawings which illustrate the invention, like characters indicate like parts throughout the several views.

Referring to the drawings:

Figure 1 is a plan view of the improved 30 side bearing;

Fig. 2 is a view partly in side elevation and partly in longitudinal vertical section taken on the line 2—2 of Fig. 1;

Fig. 3 is a horizontal section taken on the 35 line 3—3 of Fig. 2;

Fig. 4 is a transverse vertical section taken on the line 4—4 of Fig. 2;

Fig. 5 is a detailed view principally in 40 section taken on the line 5—5 of Fig. 2; and

Fig. 6 is a view corresponding to Fig. 2 but illustrates the movable parts of the side bearing moved to one of their extreme positions.

The numerals 7 and 8 indicate, respectively, the body bolster and the truck bolster of a railway car.

The improved side bearing is carried by a body bolster 7, and includes a cast rectangular housing 9, with an open top and bottom. 50 Cast with the upper portion of the housing 9, at the corners thereof, are four horizontally disposed ears 10, having bores 11, through which rivets or other fastening means, not shown, are passed to rigidly secure the side bearings to the body bolster 7.

The top surfaces of the housing 9 and ears 10, extend in an oblique plane to conform to the surfaces of the body bolster to which they are secured and have flat engagement therewith.

On the inner surfaces of the end walls of the housing 9 are shoulders 12 on which is loosely supported a cover 13, which fits within the housing 9 and is held thereby, against horizontal movement. The upper surfaces 65 of the cover 13 extend in the same oblique plane as the upper surfaces of the housing 9 and ears 10, so as to bear directly against the body bolster 7. The top of the cover 13 is cored for the sake of lightness and the 70 saving of material. The ends of the cover 13 terminate short of the respective ends of the housing 9 and cast therewith, at the bottom thereof, are small flanges 14, provided for a purpose that will presently appear. 75 On the bottom of the cover 13, at the ends thereof, are guides 15 which slidably receive and support a wearing plate 16. When the cover 13 is in position in the housing 9 the wearing plate 16 is held thereby, against removal from the guides 15.

In each end of the housing 9, is formed a pocket 17 and extending into the housing, at the bottom of each pocket, is a bifurcated bracket 18. On the bottom of the pockets 17 85 and on the upper faces of the brackets 18 are formed roller seats 19 that have diverging contours which extend from the centers thereof.

A pair of rollers 20 are mounted in the 90 seats 19 and support the ends of a self-centering carrier 21 in the form of a single bar. The ends of the carrier 21 work in the pockets 17 and have on their lower edges, roller seats 22 of the same shape as the roller seats 95 19 with the exception that they are inverted with respect thereto. A pair of longitudinally spaced fulcrum notches 23 are formed in the upper edge of the carrier 21. Hub-like stops or extensions 24 are formed 100 on the vertical faces of the carrier 21 centrally between the notches 23.

The body bolster 7 is supported from the truck bolster 8 by a pair of rockers 25, located, the one in advance of the other. These 105 rockers 25 are provided with apertures 26 which extend in the direction of the rocking movement thereof and through which aperture the carrier 21 extends. Fulcrum pins 27 carried by the rockers 25, in the aper- 110

tures 26, extend through the fulcrum notches 23 and are normally out of engagement therewith. The upper segmental bearing surface of the rocker 25 supports the wearing plate 16 and the lower segmental bearing surfaces thereof, rest on a bearing plate 28 secured to the truck bolster 8.

Normally the rockers 25 rest on the wearing plate 28 and support the car body and load through the wearing plate 16 and cover 13. When the load is thus supported the fulcrum pins 27 are entirely out of contact with the fulcrum notches 23 and as long as the load continues on the rockers the movement is simple and said rockers will move back and forth on the wearing plates and carry with them the carrier 21.

When the car is on a curve the rockers 25 will be positioned, as shown in Fig. 5, to a greater or less degree and as the rockers 25 are interlocked to the carrier 21 by the notches 23 and pins 27, said carrier will be moved therewith. This movement of the carrier 21 moves certain of the inclined surfaces of its roller seats 22 onto the rollers 20 and also moves said rollers onto certain of the inclined surfaces of the roller seats 19. With the rollers 20 thus positioned in the roller seats 19 and 22, the carrier 21 is lifted into a position to bring the fulcrum notches 23 in said carrier into close relation to the fulcrum pins 27.

If the rockers 25 continue to support the load from the wearing plate 28 until the car passes beyond the curve the movable parts of the side bearing will return to normal positions under the action of the bolsters with respect to each other, but if the car body lifts with respect to the car truck, the carrier 19 will lift the rockers 25 out of engagement with the wearing plate 28 and said rockers will then swing on the fulcrum pins 27, in the fulcrum notches 23, into perpendicular or normal positions. This swinging movement of the rockers 25 will carry with them the carrier 21, which carrier will at the same time assist in positioning the rockers. The rollers 20 and carrier 21 will at the same time self-center themselves and also assist in positioning the carrier 19. It will thus be seen that the rockers 22 will instantly return to normal positions and will again be ready to support the load when the car body again assumes a normal position. Extreme movements of the rockers 25 are limited by engagement thereof with the hubs 24 and flanges 29 on the lower inner edges of the ends of the housing 9, (see Fig. 5).

In assembling the improved side bearing the rollers 20 are first mounted on the seat 17 and the end portions of the carrier 21 inserted through the apertures in said rockers and the pins 27 interlocked with the notches 23. The assembled rockers and

carrier are then placed in the housing with the ends of said carrier resting on the rollers 20. The wearing plate 16 is then secured to the cover 13 and said cover placed in the housing and supported on the shoulders 12. To hold the parts in assembled relation before the side bearing is secured to the body bolster, the upper edges of the end walls of the housing 9 are bent inward as indicated by broken lines at 30 by pounding or otherwise so that they will overlie the flanges 14 on the ends of the cover 13 and thereby hold said cover in position.

What we claim is:

1. In a side bearing, the combination with 80 a body bolster and a truck bolster of a housing secured to the body bolster of a pair of self-centering rollers mounted in the housing, a self-centering carrier bar having its ends mounted on the rollers, a rocker 85 having an aperture extending in the direction of the movement of the rocker and through the aperture the carrier bar loosely projects, said rocker normally supporting the body bolster from the truck bolster, said carrier bar and rocker having coöperating 90 normally separated fulcrum surfaces, the fulcrum surface of the rocker being above the center of gravity thereof.

2. In a side bearing, the combination with 95 a body bolster and a truck bolster of a housing secured to the body bolster, a pair of self-centering rollers mounted in the housing, a self-centering carrier bar having its ends mounted on the rollers, a rocker 100 having an aperture extending in the direction of the movement of the rocker and through which aperture the carrier bar loosely projects, said rocker normally supporting the body bolster from the truck bolster, said carrier bar and rocker having 105 interlocking normally separated coöperating fulcrum surfaces, the fulcrum surface of the rocker being located above the center of gravity thereof.

3. In a side bearing the combination with 110 a body bolster and a truck bolster of a housing secured to the body bolster, a pair of self-centering rollers mounted in the housing, a self-centering carrier bar having 115 its ends mounted on the rollers, a rocker having an aperture extending in the direction of the movement of the rocker and through which aperture the carrier bar loosely projects, said rocker normally supporting the body bolster from the truck bolster, said carrier bar having a fulcrum 120 notch and said rocker having a fulcrum pin loosely extending through said notch, said pin being located above the center of gravity 125 of the rocker.

4. In a side bearing the combination with 130 a body bolster and a truck bolster, of a housing secured to the body bolster, a pair of self-centering rollers mounted in the

housing, a self-centering carrier bar having its ends mounted on the rollers, a pair of rockers having alined apertures extending in the direction of the movement of the 5 rockers and through which apertures the carrier bar projects, said carrier and rocker having normally separated interlocking fulcrums whereby a movement of the one will impart a movement to the other, said carrier 10 having lateral extensions located be-

tween the rockers for limiting the movements thereof.

In testimony whereof we affix our signatures in presence of two witnesses.

EDWIN W. WEBB.
NICHOLAS C. THALHEIMER.
